ANE P. SCHAT, OF SAN FRANCISCO, CALIFORNIA.

ADJUSTABLE INCLINED DAVIT.

1,369,132.

Specification of Letters Patent. Patented Feb. 22, 1921.

Application filed March 29, 1919. Serial No. 286,018.

To all whom it may concern:

Be it known that I, ANE P. SCHAT, a citizen of the Netherlands, residing at San Francisco, in the county of San Francisco and State of California, have invented certain new and useful Improvements in Adjustable Inclined Davits, of which the following is a specification.

My invention relates to hoisting and lowering devices, and is specially adapted for use as a davit for ships.

Some of the leading features of the invention are closely related to those set forth in my pending application #230,106 and 15 #259,790, one object being to provide a rotatable davit which, when released from its normal position will swing outwardly by gravity, thus insuring that the lifeboats will be automatically brought into position to 20 be lowered into the water without the application of mechanical force.

Another very important object is to provide brake mechanism for controlling the davit to prevent too free a rotation thereof, 25 and for locking it in any given position when desired.

A further object is to provide means for supporting the davit in the same plane at different angles of inclination, and in different planes, whereby to regulate the power 30 of its automatic movement, and to predetermine the direction of its movements.

Still another object is to provide a davit adapted to be controlled and operated from 35 the upper deck of a ship, while being supported on the second deck, or in any event at a point materially below said upper deck, whereby to utilize the ship itself, for the most part, as a frame for supporting and controlling the davit, and for bringing the point 40 at which the weight is supported as close to the water as possible.

Further objects will appear in the subjoined description.

In considering the operation of the device, it should of course be borne in mind that each boat is supplied, as is usual, with two davits (one at each end thereof) which 45 rotate toward each other.

An important feature of the construction shown in the drawings consists of a davit mounted at its lower end in a socket on the second deck of a ship, and provided on the upper deck with adjustable means for rotatably holding the davit at any desired degree of inclination, and for causing the

lower portion of the davit to swing inboard and outboard in a vertical plane at any desired angle to the longitudinal extent of the ship.

The invention consists in certain novel features of construction and arrangement of parts, as will be hereinafter described and claimed, reference being had to the accompanying drawings, in which:

Fig. 1 is a side elevation of one of my improved davits, with certain parts shown in section, the normal position of the davit being shown in full lines, and its innermost and outermost positions in dotted lines.

Fig. 2 is a fragmentary top plan view, on an enlarged scale, showing one form of brake mechanism which I employ for controlling the rotation of the davit, the brake wheel and davit being shown in section.

Fig. 3 is a top plan view of the adjustable guide mechanism employed with my davit to predetermine the direction of its outboard movement, relatively to the longitudinal extent of the ship, and to guide the davit in 80 said movement.

Fig. 4 is an inverted plan view showing the outer end of the guide plate disconnected from the parts with which it cooperates;

Fig. 5 is a top plan view of the base plate on which the guide plate rotates.

Referring further to the drawings, the numeral 1 indicates the upper deck of a ship, and the numeral 2 the lower deck, which latter is provided with a suitable support 3 having a socket 4 designed to receive the lower end of the davit 5 to form a ball and socket joint therewith, whereby to adapt the lower end of the davit for universal movement on its support 3.

On the upper deck 1 of the ship is the guide plate 6, having its outer end portion 6^a projecting over the side of the ship, and this projecting portion is provided with a longitudinal slot 7 through which the davit passes. When the davit is standing in a true vertical position on its support 3, it passes through the slot 7 at the point indicated by 5^x in Fig. 3, and the guide plate 6 is so constructed that it rotates around this point 5^x as a center; from which it will be seen that by a suitable rotation of said guide plate, the davit may be made to swing outboard at any desired angle relatively to the longitudinal extent of the ship; and in thus swinging in and out, it will always move in

a true vertical plane, which latter would not be possible if the center of rotation 5^x of the guide plate 6 were located inboard, or at any point out of true vertical alinement 5 with the center of the socket 4. But the guide plate cannot be provided at the point 5^x with a pivot upon which to rotate, because, in the first place, that point is overboard, and secondly, because it is in the 10 path of the davit as it moves to its inboard position. Therefore, in order to cause the plate 6 to rotate around the center 5^x , I provide the outer end portion 6^a of said plate, on its under side, with a 15 circular tongue 6^b , and this projecting end 6^b of said guide plate I mount on the base plate 8 which is rigidly secured to the deck of the ship, and has a circular groove 8^a adapted to rotatably receive the tongue 6^b 20 to rotate therein, the common center from which said tongue and groove are struck being at the point 5^x when the parts are in their operative position relatively to each other.

25 The outer end 6^a of the guide plate is further provided with a curved slot 9, also struck from the center 5^x ; and working in this slot is a bolt 10 for suitably holding and locking the end 6^a of the guide plate in engagement with the base plate 8.

At the inner end of the guide plate 6 is a segmental locking plate 11 rigidly secured to the deck of the ship, and provided with a slot 12 also struck from the center 5^x , and 35 in this slot is received a locking bolt 13 carried by the flange 14 at the extreme inner end of the guide plate, which flange projects underneath the inner edge of the locking plate 11. Hence it will be seen that the 40 guide plate 6 will be very securely held in any position to which it is adjusted, being locked at its outer end to the base plate 8, and at its inner end to the locking plate 11.

The plate 11 may be made to include as 45 great an arc of a circle as the needs of each case may require.

My davit has two distinct movements: first, its rotary movement which does not change the angular position of the lower 50 portion of the davit, but causes its upper portion to swing around by gravity when the davit is in its normal inclined position; and secondly, its outboard and inboard movement in which the entire davit is rocked 55 inwardly and outwardly on the ball and socket joint at the lower end thereof, the davit being guided in this movement by the slot 7 of the guide plate.

This rocking movement of the davit on its 60 lower end is preferably controlled by a screw mechanism having an internally threaded pipe 15, and a coöperating externally threaded pipe or bar 16, the pipe 15 being bifurcated at its outer end to form the 65 branches 15^a for pivotal engagement with

the davit, and the threaded bar 16 being supported at its inner end by the post 17 at the inner end of the guide bar 6. A short bar or shaft 18 is rotatably mounted in the post 17, and is held against endwise movement 70 therein by the two collars 19 rigidly secured to said shaft, one on either side of said post. The shaft 18 and the threaded bar 16 are connected together by means of a universal joint 20.

75 On the outer end of the shaft 18 is a hand wheel 21 for rotating the same to operate the screw mechanism of the davit. The co-operating parts 15 and 16 of this mechanism constitute a thrust screw for imparting to 80 the davit a very positive inward and outward movement when occasion requires.

At the outer bifurcated end of the threaded pipe 15, I provide the davit with a brake wheel 22 rigidly secured to the davit 85 and received between the branches 15^a at the end of the pipe. For this wheel I provide any suitable brake mechanism of ordinary or preferred construction. For the purposes of this application I have deemed it 90 sufficient to simply show a strong band brake 23 provided on diametrically opposite sides of the brake wheel with rigid bosses 24, and terminating in two end sections 95 approximately parallel with each other, and provided with a clamping screw 26. The bosses 24 have pivotal connection with the branches 15^a by means of the pivots 27.

When the davit is standing in an inclined position (for instance as illustrated in full 100 lines in Fig. 1, which is its normal position), with its upper portion turned more or less away from the direction in which the davit is leaning, the davit will have a tendency to swing around by gravity, and the greater 105 its inclination, the greater will be its tendency to thus rotate. Hence, when the lifeboat chock, with which this davit is intended to coöperate, collapses and suddenly 110 throws the weight of the boat on the davit, the davit is liable to rotate too suddenly, especially if the ship chances to pitch or tilt in a direction to increase the outward inclination of the davit. In cases of this kind, or when heavier loads than had been anticipated, are suddenly thrown upon the davit, the brake serves a most useful purpose in preventing the boat from being automatically pitched too suddenly overboard. It 115 will therefore be seen that with my inclined davit the brake serves a most useful purpose in checking its momentum as it rotates outwardly. It also serves a further very useful purpose, in providing means for 120 locking the davit at any desired point of its rotation. This is especially desirable when the davit is in its extreme outboard and inboard positions where it is very desirable that it should not be rotating back and forth 125

as the ship rocks, or the winds blow, or other slight forces operate upon it, or upon

the load it is supporting

In order that the band brake 23 may be 5 amply strong to support the weight imposed upon it at times, and may yet be flexible enough to operate well as a brake, I may make it as broad as may be necessary and 10 make the brake wheel 22 correspondingly long. The brake wheel is provided at its ends with annular outwardly extending flanges 22^a to hold the band brake against longitudinal movement on the brake wheel.

The strain imposed upon the band brake 15 by the resistance which it offers to the rotation of the davit imposes a lateral strain upon the thrust screw arrangement, and to prevent this strain from ever buckling or bending the threaded telescoping parts 15 20 and 16 in a way that might prevent them from working properly, I erect upon the guide plate 6 a second post 28 provided with a slot 29 through which the threaded pipe 15 passes. This post will resist any 25 sudden or excessive lateral strain that the brake may ever impose upon the thrust screw.

The larger section 15 of the thrust screw arrangement is placed outwardly next the 30 davit because its greater diameter adapts it to offer greater resistance to the lateral strain imposed upon the thrust screw arrangement by the brake, which strain is of course greatest at the outer end of the thrust 35 screw adjacent the post 28.

The guide bar 6 is provided with the lateral extensions 6^a on opposite sides of the post 28 to widen said bar at that point to prevent the lateral strain imposed upon the post 40 28 from imparting a twisting strain to the guide bar. The slot 29 is sufficiently long to permit the member 15 of the thrust screw to move downwardly without interference when the davit is rocked to its lowest 45 outward position.

The section 15 of the thrust screw may be provided on its outside with a loose-fitting section of pipe 30 (as indicated in dotted lines in Fig. 1) if desired, which pipe can be 50 used as a cover for the exposed threaded portion of the screw bar 16, when the davit is standing idle.

The universal joint 20 will enable the thrust screw to operate the davit equally 55 well in all positions.

The thrust screw and the guide plate 6 always extend in the same longitudinal direction; when one is adjusted to a different position, the other is moved with it, so that 60 their relative longitudinal relation to each other is not changed but remains always the same; and the vertical plane, in which these two parts always lie, extends centrally through the socket at the lower end of the 65 davit, so that the lower portion of the davit,

as it rocks inwardly and outwardly on its socket support 4, always moves in this same vertical plane

To sum up!—It will be seen, first, that I have provided a davit which normally 70 stands with its lower portion in an inclined position, and has adjusting means for changing its inclination to any desired angle; secondly, that the davit will tend to automatically swing around by gravity and come 75 to rest in a vertical plane extending longitudinally of the guide plate whenever the lower portion of the davit is inclined toward one end or the other of said plate, and that the greater the inclination of the davit, as a 80 whole, the stronger will this tendency be; thirdly, that since the guide plate is rotatable around the point 5^a, it may be caused to extend longitudinally toward any desired point of the compass, and thereby the point 85 toward which the davit shall tend to move and come to rest can be accurately predetermined, so that the davit may be adjusted to swing overboard and come to rest at any desired angle to the longitudinal extent of 90 the ship; fourth, that the movement of the davit in any desired direction is not left dependent upon the tendency imparted to the davit by the adjusting means to move it in that direction, but that it is further provided 95 with means for positively guiding it and forcing it to move in the predetermined direction; and, fifth, that it is provided with 100 brake mechanism for checking its movement, or locking it at any desired point in its rotation.

As to the operation of my davit, it is only necessary to add that when a lifeboat is to be placed on the chocks, the davit is drawn inboard by means of the thrust screw arrangement, till its lower portion has passed the vertical and reached its innermost position, inclining slightly inboard, as indicated in dotted lines in Fig. 1. It will then have a slight inclination to automatically rotate 110 inwardly, and hence when the brake is released, the boat can be most easily drawn inboard into position to be lowered onto the chocks. When the boat is secured on the chocks, the davit is rotated till its upper 115 end is brought into its normal angular relation to the longitudinal extent of the ship, and then the brake is applied again. The davit is then bodily rocked outwardly by means of the thrust screw into its normal operative position, as illustrated in full lines in Fig. 1, and the tackle connecting it with the lifeboat is properly adjusted. It will now be seen that when the chock collapses, 120 and the weight of the boat is thrown upon the davit, the davit will automatically swing the boat overboard, in position to be lowered into the water.

When the weather is rough and there is 125 danger of bumping the lifeboat against the 130

a guide for the davit to hold it against rocking bodily in a plane at right angles to the longitudinal extent of the thrust mechanism and to relieve the thrust mechanism from lateral strain when in its extended outboard position.

15. In a device of the character described, a davit mounted for universal rocking movement; a rotatable guide provided with 10 a guideway, said guide having its center of rotation in said guideway at a point in vertical alinement with the center upon which the davit rocks; actuating mechanism for rocking the davit bodily back and 15 forth in said guideway; and means for adjusting the guide with its guideway to extend toward different points of the compass, to adapt the davit to rock in any desired direction.

20. 16. In a device of the character described, a davit mounted for universal rocking movement; a rotatable guide provided with a guideway, said guide having its center of rotation in said guideway at a 25 point in vertical alinement with the center upon which the davit rocks; actuating mechanism for rocking the davit bodily back and forth in said guideway, said actuating mechanism extending in the same direction as said guideway and being adapted 30 to rotate with said guide; and means for adjusting said parts to extend in different directions, whereby to impart to the davit positive guided movement in any desired 35 direction relatively to the longitudinal extent of the ship.

17. In a device of the character described, a davit mounted for universal movement on the second deck of a ship and extending 40 upwardly above the upper deck, the upper and lower portions of the davit being disposed at an angle to each other; means on

the upper deck for normally holding the lower portion of the davit to rotate on its longitudinal axis, normally in an inclined 45 position, and for otherwise controlling and operating the davit, said means comprising a rotatable guide plate having a portion extending outwardly beyond the upper deck provided with a guideway, said guide having its center of rotation in said guideway at a point in vertical alinement with the center upon which the davit rocks; a post at the inner end of said guide plate; thrust screw mechanism journaled in said post at its inner end and engaging the davit at its outer end with a universal joint near its inner end adjacent said post; a friction lock for engaging the davit at the outer end of the thrust mechanism; a second post 50 mounted on the guide plate near the outer end of the thrust mechanism and provided with a slot through which the thrust mechanism passes, whereby to brace said mechanism against the lateral strain imposed 55 thereupon by the lock; and a segmental plate at the inner end of the guide plate provided with means for rigidly securing the guide plate at any desired angle of adjustment, whereby to adapt the davit to 60 rock in any desired direction.

18. In a device of the character described, a davit having its upper and lower portions disposed at an angle to each other and normally held in an inclined position to cause 75 the davit to rotate by gravity; means for adjusting the davit to different angles of inclination; a non-rotatable member adapted for frictional engagement with the davit in all its positions, to form a brake for 80 regulating the degree of frictional engagement between said parts.

In testimony whereof I affix my signature.
